UNITED STATES PATENT OFFICE.

AMOS RANK, OF SALEM, OHIO.

IMPROVEMENT IN RAILROAD-CHAIRS.

Specification forming part of Letters Patent No. 44,155, dated September 27, 1864.

To all whom it may concern:

Be it known that I, AMOS RANK, of Salem, county of Columbiana, State of Ohio, have invented a new and Improved Railroad-Rail Chair; and I do hereby declare that the following is a full, clear, and exact description thereof, reference being had to the accompanying drawings, making a part of this specification, in which—

Figure 1 is a top view showing my chair applied at the joint of two sections of railroad-rails. Fig. 2 is a side view of Fig. 1. Fig. 3 is a bottom view of Figs. 1 and 2. Fig. 4 is a central section of the two parts of the chair and views of the rail, wedge, and key. Fig. 5 is a central section taken vertically and transversely through the chair when secured to a rail. Fig. 6 is a longitudinal section taken in a vertical plane through Figs. 1, 2, 3, and 5.

Similar letters of reference indicate corresponding parts in the several figures.

The object of my invention is to so construct a two-part railroad-rail chair, having cheeks for supporting the rail-head on each side, that the base of one part of this chair shall interlock and break joints with the base of the opposite part thereof, thus affording a firm and substantial base-support for the rail at the joints, as will be hereinafter described.

Another object of my invention is to construct a two-part double-cheek rail-chair, which, when properly secured down in place at the joints of rails, shall support the same at the base, at the web or neck, and also at the lips of the rail-head, said supports being so formed or applied that they shall all break joints with the rail-joint, as will be hereinafter described.

To enable others skilled in the art to make and use my invention, I will describe its construction and operation.

In the accompanying drawings, A A represent the ends of two sections of railroad-rails, which have notches *a* cut horizontally through their webs to receive a flat bolt, *b*. These notches, when the ends of the rails are brought together, form a slot, which is somewhat longer than the width of the flat bolt *b*, and thus provision is made for the longitudinal expansion and contraction of the rails.

B B' represent the sections of my two-part chair. These sections are each cast or otherwise formed with a cheek, *d*, which is curved

in such manner as to conform to the sides of the rail and to support the lips of the rail-head, as shown in Figs. 2 and 5. The base plate of each section projects out from both sides of the cheeks *d*, and those portions of said plates which are lettered *c c* are perforated to receive the hold-down spikes that secure the whole down on the cross-ties, while those portions projecting from the opposite sides of their respective cheeks are intended to serve as supports for the base of the rail. These latter portions of the chair are constructed as follows: That portion of the chair lettered *B* has a tongue, *g*, formed on it, which, when the two parts of the chair are brought together, fits into a recess formed between the two tongues *g' g'*, projecting from the part *B'*, and thus we have an interlocking orlapping joint. The tongue *g* is at an intermediate point between the ends of the chair, and extends across the base of the rail, directly under the joint thereof. The tongues *g' g'* are of the same length as the central tongue, and these support the rail on each side of its joint. By this mode of constructing a chair it will be seen that I obtain all the advantages of a solid base directly beneath the rail-joint, and at the same time avoid the objections to the solid or single double-cheek chair. My chair can be readily applied to or removed from a rail without moving the sections thereof out of line or loosening other parts of a rail-section for this purpose.

Another advantage which my two-part chair possesses over the common chair is that the interlocking joints break joints with the joint of the rail, and when the two portions *B B'* are spiked down there will be no longitudinal thrust of one of these portions without the other, and as each one of these portions has a very wide base liability of the cutting of the rail will be to a great degree obviated.

I employ as a means for securing the two parts of the chair to the sides of the rail, irrespective of the spikes which are driven through the outer portions of the chair base, a flat bolt, *b*, above referred to, which also breaks joints with the rail-joint and serves as an additional security against the loosening of the rails. The head of this bolt is countersunk into the cheek of the portion *B*, and the flat shank of this bolt passes laterally through the rail and opposite cheek and receives

through its projecting end a wedge-pin, *h*, which passes down vertically into a hole in this latter cheek, thus drawing together and holding the two parts of the chair firmly in contact with the sides and bottom of the rail.

Having thus described my invention, what I claim as new, and desire to secure by Letters Patent, is—

1. A two part railroad-rail chair which is constructed with double supporting cheeks *d d*, interlocking base portions *g g' g'*, and a

laterally-holding bolt, *b*, passing through the neck of the rail, substantially as described.

2. The combination of the tongues *g g' g'*, cheeks *d d*, flat bolt *b*, and key-pin *h*, with the slotted end rails, *A A*, substantially as described.

AMOS RANK.
